UNITED STATES PATENT OFFICE.

ARTHUR A. JOHNSON, OF WASHINGTON, DISTRICT OF COLUMBIA, ASSIGNOR TO
UNDERWOOD TYPEWRITER COMPANY, OF NEW YORK, N. Y., A CORPORATION
OF DELAWARE.

TYPEWRITING MACHINE.

Application filed April 27, 1921. Serial No. 464,963.

To all whom it may concern:

Be it known that I, ARTHUR A. JOHNSON, a citizen of the United States, residing in Washington, District of Columbia, have invented certain new and useful Improvements in Typewriting Machines, of which the following is a specification.

This invention relates to the fan-fold type of typewriting machines and more particularly to a tally-strip mechanism therefor.

In typewriting machines, generally, it is old to provide a tally-strip mechanism for the purpose of supporting and feeding a tally-strip or record strip of paper so that said strip extends around the platen of the machine to receive carbon impressions of certain of the data written upon the work-sheets.

In the fan-fold type of machines having a rotary platen, the platen is mounted in its carriage so that it can be swung up into position where the course of the web is straightened sufficiently to enable the carbon sheets to be shifted to a new position with respect to the web. This is done after each "form" has been written upon and preparatory to the writing of the next form.

A feature of the present invention is the provision of means and the arrangement and location of parts for supporting and guiding a tally-strip (and its associated carbon strip, if such is used) so as to permit the swinging of the platen to carbon-shifting position.

Another feature of this invention is the provision of means and arrangements and location of parts whereby the reaches of the tally-strip (and its associated carbon strip) that extend to and from the platen are substantially taut in the normal and carbon-shifting positions of the platen around which said strip is looped, so as not to interfere with the operation of the machine or to be interfered with by the machine in operation.

Preferably both the receiving roll and the supply roll of the tally-strip are mounted directly on the carriage, where they do not become disconnected from the line-spacing mechanism during the upward displacement of the platen frame. These spools occupy positions above the work-webs when they are straightened out, so as not to form

an objectionable obstruction to the manipulation of the webs. 55

Preferably the tally-strip, which extends from the supply roll to the receiving roll around the platen, is slack while the platen is being displaced or swung from and to normal and carbon-shifting positions, and is also substantially taut when the platen is in either position.

In the accompanying drawings—

Fig. 1 is a side elevation of a "fan-fold" machine showing the tally-strip mechanism 65 attached thereto.

Fig. 2 is a front view showing the platen, and the tally-strip extending around the platen.

Fig. 3 is a detail side elevation showing 70 the tally-strip feed mechanism.

Fig. 4 is a sectional side elevation of the typewriter carriage showing the location of the tally-strip mechanism and guiding means. 75

Fig. 5 is a sectional side elevation showing the platen in carbon shifting position.

In the Underwood "fan-fold" typewriting machine such as is shown in the patent to Smith 1,177,546, the rotary platen 10 is 80 mounted to rotate in a platen swinging frame 11, which in turn is pivotally mounted on a front rod 12 supported by the platen carriage 13. Being so mounted, the platen swinging frame 11 may be moved by hand 85 from the full-lined position shown in Fig. 4, to the dot and dash line position shown in said figure.

The "fan-fold" or separate work-webs, if such are used, are guided over a supplementary carriage frame 14, which is suitably supported and connected to the typewriter carriage 13 at 15 to travel therewith in letter feed direction. The carriage frame 14 is provided with means 16 for holding superposed carbon sheets between the folds of the folded web or the separate webs. The work-webs and carbon sheets are thence led over the paper table 17, carried by the typewriter carriage 13, and down around the platen 10 100 to printing position. A paper table 18 is provided on the swinging frame at the delivery side of the platen for supporting the delivered work sheets and for other purposes. After a "form" has been written, the 105 platen frame 11 is swung upwardly and for-

wardly about its pivot 12 to straighten the course of the web, to permit the carbon sheets to be retracted to new position in the web, after which the web is gaged, and the 5 platen is then returned to normal position.

In the course of typewriting the platen is moved in line-space direction by the usual pawl 18^a and ratchet 18^b, to which the platen is connected by means of a gear similar to 10 the gear 19 and which is secured to the ratchet, an idle pinion similar to the gear 21 secured to the platen shaft 22, to which the platen is also secured. The usual detent 23, engages the ratchet 18^b, and holds the 15 ratchet in line-space position. The usual feed rolls 24 and 25, co-operate with the platen to feed the work sheets with rotation thereof.

It will be noted that in the "fan-fold" 20 typewriting machines the platen 10 has a considerable extent of movement to and from normal position on the typewriter carriage.

The tally-strip mechanism of the present 25 invention may in some details embody features that are shown in the patent to Hart 1,281,160. It comprises a supply roll 26, and a receiving roll 27, secured, respectively, to shafts 28 and 29, which are journaled in 30 brackets 30^a, secured to the side of the carriage 13, and thus both the supply spool 26 and the receiving spool 27 may be mounted independently of the swinging frame 11 which carries the platen around which the 35 tally-strip is looped.

The tally-strip 30, and its associated carbon-sheet strip, if such is used, are fed around the platen 10 line-by-line, by the rotation of the receiving spool 27, which rotation may be caused by the operation of 40 line-space mechanism provided upon the carriage and not shifting with the platen-swinging frame. The illustrated means for doing this comprises a ratchet 31 fixed 45 to the shaft 29 of the receiving spool and a pawl 32 to engage the ratchet wheel 31 and move the same by an arm 33 pivotally mounted on a shaft 29. The arm 33 carrying the pawl 32 is connected by a link 34 to 50 the slide 25 of the usual line-space mechanism which carried the pawl 18^a, for the platen ratchet 18^b. A suitable spring maintains the pawl 32 in engagement with the ratchet wheel 31. The arrangement is such, 55 that, when the line-space slide 35 moves rearwardly to rotate the platen, the link 34 swings the arm 33 sufficiently to cause the pawl 32 to rotate the shaft 29 and wind the tally-strip 30 and its carbon on the receiving 60 spool 27 and thus feed the tally-strip a suitable distance to space the items thereon. Any suitable feeding mechanism for the tally-strip may be employed without departing from the spirit of my invention, the 65 feeding mechanism described and illustrated

being merely conventional. Inasmuch as the strip-winding devices are mounted upon the main carriage, no disconnection occurs between the spools and the winding means when the platen-frame is swung up. 70

The tally-strip 30 engages the platen 10 out of the range of the feeding rolls 24 and 25, as shown in Fig. 2, and thus may be line-fed independently of the rotation of the platen, if desired. 75

In order to permit the platen to be moved to carbon shifting position without interference from or undue tensioning of the tally-strip, I preferably mount the tally strip supply roll 26 in such a position on the carriage 80 that there will be a slack in the free stretch 36 of sufficient extent to permit the platen to move backwardly and then forwardly during the platen-displacing operations in the loop of the tally strip. The rolls can be so positioned that the slack will be produced by the platen itself in moving away from normal position, the supply and receiving rolls being mounted, as shown in the drawings, upwardly and rearwardly of the 85 platen, and this position of the rolls may be described as being above the path of the straightened-out work-webs and below the paper-table on the swinging frame, or between the latter and the paper-table on the 90 carriage.

Of course, it is not essential to the present invention that the rolls 26 and 27 be mounted in this particular position, although in some cases it is preferable, because it is sufficient 100 if the tally strip be guided to said position from strip-controlling rolls which may be mounted elsewhere. It is desirable that the strip lead to the platen from this point or its equivalent and return from the platen to 105 substantially the same point, if the receiving means for the strip is to be mounted on the carriage frame. If the receiving means is to be mounted on the platen frame it is not essential where the part of the tally strip at 110 the delivery side of the platen leads to.

Where supply and receiving rolls are provided it is inconvenient to have the rolls in such close proximity that the strip starts and returns to substantially the same point, 115 therefore, I have provided a guide 37 whose function is to engage the stretch 36 of the web between the platen and the supply roll 26 and bring a part of the same into close proximity with the receiving roll. There are 120 other ways of doing this, but the specific arrangement shown is the one I prefer at the present time, it being understood that my invention in its broader aspect includes any suitable means for bringing about the same 125 result.

It will be noted that at the lower end of the paper table 18, there is preferably provided a rounded guide 37^a which engages the stretch 36 of the tally strip between the 130

platens and the receiving roll 27. This guide serves to reduce the friction and to facilitate the passage of the strip under the table 18, but has in addition another function and 5 that is to provide normally a slight bend or tensioning 38 in the strip so that immediately the platen is moved from normal position a slight slack will be provided in the strip. The paper table may move at a 10 greater speed than the rotation of the platen caused during the shifting by its planetary movement around the gear which connects it to the line space wheel, the latter being held against movement by the 15 detent. This has the effect of preventing the platen from feeding the strip off the supply roll during the planetary movement. The same is true when the platen is just about in writing position on being returned, the 20 slight slack being maintained until the very last portion of the movement when the guide 37^a causes the strip to be taut.

In operation, when the platen is to be shifted to carbon retracting position, the 25 guide 37^a may permit a slight slack, then the platen moves rearwardly and upwardly through the loop formed by the tally-strip, then, on reaching its extreme rearward position, the platen moves forwardly to its 30 position of rest when it again may cause the loop to be substantially taut. In this taut position the tally-strip will not interfere with the movement of the web or webs while the latter are being adjusted and 35 gaged. The reverse is true when the platen is returned to writing position.

The guide 37 may be in the form of a roller 39 rotatably mounted upon a rod 40 suitably supported by the carriage.

40 The supply roll 26 may be provided with friction device 41 whereby the strip is held against accidental movement.

Variation may be resorted to within the 45 scope of my invention and portions of the improvements may be used without others.

I claim as my invention:

1. A tally-strip mechanism for manifolding typewriting machines of the rotary platen type in which the platen is shiftable in its carriage to position to free the work-webs to permit the retraction of the 50 carbon-sheets from the work-webs, comprising tensioning means for the tally-strip, parts of which tensioning means are mounted on the carriage, the strip passing around the platen, and said tensioning means causing the strip to be substantially taut when the platen is in writing position, and slack during the shifting movements of the platen 55 to and from writing position.

2. In a manifolding typewriting machine, the combination of a carriage; a platen; a platen frame in which the platen is mounted to swing upwardly and forwardly away from normal position, and a 60

tally-strip mechanism having a supply spool and a receiving spool both mounted independent of said platen frame and supported by the carriage, said tally-strip mechanism having guiding means and being so arranged that the free stretches of the tally-strip will be substantially taut in both normal, and upward and forward positions of the platen. 70

3. In a manifolding typewriting machine, the combination of a carriage; a swingable frame; a platen mounted in said swingable frame; a paper table on said carriage; a paper table on said swingable frame; a tally-strip supply spool and a receiving spool mounted on said carriage and located above the carriage paper table and below the swinging frame paper table; and means for guiding the tally-strip between the last mentioned paper table and the 85 platen.

4. In a manifolding typewriting machine, the combination of a platen; a swinging frame carrying said platen; a carriage in which said swinging frame is mounted; a tally-strip supply roll mounted on the carriage, a guide over which the tally-strip is fed, said guide being in position to cause the stretch of the tally-strip which extends to the platen to remain taut in both positions of the platen. 90

5. In a manifolding typewriting machine, the combination of a platen; a swinging frame in which said platen is mounted; a carriage in which said swinging frame is 100 mounted; and tally-strip mechanism for said machine comprising a supply means and a receiving means, said supply means and receiving means being arranged in close proximity so that the free stretches of the tally strip extending around the platen will be substantially taut in both normal position of the platen and the position to which the platen may be swung so that the tally strip will not be interfered with by the 105 shifting of the platen.

6. In a manifolding typewriting machine, the combination of a platen, a carriage in which the platen is mounted for swinging movement to free the work-webs, a tally-strip mechanism comprising means by which the tally-strip is fed, the tally-strip being looped around the platen and caught by said feeding means, the latter being above the freed work-webs, line-space mechanism for 115 the platen, and means operated by the line-space mechanism for operating the means by which the tally-strip is fed, the platen being swingable to web-freeing position without unduly tensioning the strip looped there-around. 120

7. In a typewriting machine, the combination with a revoluble platen mounted for upward displacement from printing position to free the work-webs and permit relative shift- 130

- ing of webs and carbons interleaved therewith, of a tally-strip mechanism comprising a supply spool and a receiving spool, said spools being in rear of the platen and mounted to permit the displacement of said platen while the tally-strip extends from one spool around the platen to the other spool, and means for automatically line-spacing the tally-strip.
10. 8. In a typewriting machine, the combination with a revoluble platen mounted for upward displacement from printing position to free the work-webs and permit relative shifting of webs and carbons interleaved therewith, of a tally-strip mechanism comprising a supply spool and a receiving spool, said spools being mounted to permit the displacement of said platen while the tally-strip extends from one spool around the platen to the other spool, means for automatically line-spacing the tally-strip, and a work-table at the delivery side of the platen, said spools being mounted below said work-table in position for the webs to overlie the tally-strip.
15. 9. In a typewriting machine, the combination of a carriage, a frame mounted thereon, a platen mounted in said frame for displacement away from printing position to a position to free work-webs extending around the platen, a record-strip supply spool and receiving spool both mounted on said carriage, so that the platen is displaceable relatively to said spools, and automatic line-spacing mechanism for the strip, said platen being displaceable from normal to web-freeing position while the record-strip extends from one spool around the platen to the other spool.
20. 10. In a typewriting machine, the combination of a carriage, a frame mounted thereon, a platen mounted in said frame for displacement away from printing position to a position to free work-webs extending around the platen, a record-strip supply spool and receiving spool both mounted on said carriage, so that the platen is displaceable relatively to said spools, and automatic line-spacing mechanism for the strip, said platen being displaceable from normal to web-freeing position while the record-strip extends from one spool around the platen to the other spool, said platen being mounted upon a frame pivoted in front of the platen, and said spools being in rear of the platen.
25. 11. In a typewriting machine, the combination of a carriage, a frame mounted thereon, a platen mounted in said frame for displacement away from printing position to a position to free work-webs extending around the platen, a record-strip supply spool and receiving spool both mounted on said carriage, so that the platen is displaceable relatively to said spools, automatic line-spacing mechanism for the strip, said platen being displaceable from normal to web-freeing position while the record-strip extends from one spool around the platen to the other spool, said platen being mounted upon a frame pivoted in front of the platen, and said spools being in rear of the platen.
30. 12. In a typewriting machine, the combination of a carriage, a swinging frame mounted thereon, a platen mounted in said swinging frame for movement away from printing position to a position to free work-webs extending around the platen, and a record-strip feeding spool and receiving spool both mounted on said carriage, so that the platen is swingable relatively to said spools, said platen being swingable from normal to web-freeing position while the record-strip extends from one spool around the platen to the other spool, the axis of said swinging movement being in front of the platen, and said spools being in rear of the platen.
35. 13. In a typewriting machine, the combination of a carriage, a swinging frame mounted thereon, a revoluble platen mounted on said frame to swing away from printing position to a position to release the work-webs, a record-strip spool or roll mounted on said carriage, the strip leading from said roll around the platen to receive type-impressions of the data typed upon the work-webs, means for automatically line-feeding said strip, and a work-table arranged at the delivery side of the platen, said roll and strip being beneath the work-table.
40. 14. In a typewriting machine, the combination of a carriage, a swinging frame mounted thereon, a revoluble platen mounted on said frame to swing away from printing position to a position to release the work-webs, a record-strip spool or roll mounted on said carriage, the strip leading from said roll around the platen to receive type-impressions of the data typed upon the work-webs, means for automatically line-feeding said strip, and a work-table arranged at the delivery side of the platen, said roll and strip being beneath the work-table, the table swinging with the platen relatively to the roll, whereby the roll is rendered accessible.
45. 15. In a typewriting machine, the combination of a carriage, a swinging frame mounted thereon, a revoluble platen mounted on said swinging frame to swing away from printing position to a position to release the work-webs, a record-strip spool or roll mounted on said carriage, the strip leading from said roll around the platen to receive type-impressions of the data typed upon the work-webs.

upon the work-webs, means for automatically line-feeding said record-strip, and a work-table arranged at the delivery side of the platen, said roll and strip being beneath 5 the work-table, and above the line of travel of the freed webs, the table swinging with the platen relatively to the roll.

16. In a typewriting machine, the combination of a revolute platen displaceable from printing position to a position to free work-webs extending around the platen, tally-strip rolls, and means for effecting automatic line-spacing of the tally-strip, said rolls so mounted that the portion of the strip extending from one roll around the platen to the other roll may accompany the platen during the web-freeing displacement of the latter, without subjecting the tally-strip to undue tension, a work-table being provided at the delivery side of said platen to be displaced therewith, and said tally-strip passing between the platen and the work-table and being rendered accessible by the displacement of the platen and work-table.

17. In a typewriting machine, the combination of a revolute platen displaceable from printing position to a position to free work-webs extending around the platen, tally-strip spools, means for effecting automatic line-spacing of the tally-strip, said spools so mounted that the portion of the strip extending from one spool around the

platen to the other spool may move with the platen during the web-freeing displacement of the platen, without subjecting the tally-strip to undue tension, a work-table being provided at the delivery side of said platen to be displaced therewith, and said tally-strip passing between the platen and the work-table and being rendered accessible by the displacement of the platen and work-table, a line-spacing mechanism for the platen, and means connected thereto and extending to one of the spools for line-spacing the same.

18. In a typewriting machine, the combination with a revolute platen displaceable from printing position to a position to permit straightening out of the webs to free them from the interleaved carbons, to permit relative shifting of work-webs and carbons, of means, including rolls, for controlling a record-strip looped around the platen, said rolls mounted above the line of travel of the straightened-out work-web, and the platen being displaceable while the strip is looped around the same and without putting undue tension upon the strip.

In testimony whereof I affix my signature.

ARTHUR A. JOHNSON.
